RECOIL ABSORBER FOR FIREARMS

Norbert Jules André Galliot, Vancresson, and
 Jeanne Adrienne Victorine Anna Châble,
 Paris, France

Application July 8, 1935, Serial No. 30,366
 In France July 16, 1934

4 Claims. (Cl. 89—14)

The present invention relates to improvements in "muzzle checks" or recoil-absorbing apparatus for firearms, more particularly of the type comprising one or more convergent-divergent nozzles, fixed to the extremity of the barrel of the weapon, along the axis of the latter, and intended to increase the kinetic energy of the gases, which are thereafter diverted and rejected to the exterior by means of a fixed deflector-system, single or multiple, generated by the revolution of one or more arcs around the longitudinal axis of the weapon; the energy of the gases which escape from the muzzle, is utilized to exert a force of traction in the contrary direction to the force producing the recoil of the weapon.

It is found with these apparatus in general, when it is desired to obtain a suitable efficiency, that they reject rearwardly burning and toxic gases of a nature to incommode the pointers and gun-servers, and have large weight and bulk, situated at the point where these characteristics have the most disadvantages, at the chase of the weapon.

Numerous devices have been thought out in order to obviate these defects, in particular in order to trap the gases, to expand them and thereafter to send them back in a harmless direction, namely, even towards the front.

The device according to the invention proceeds from another idea; it tends to create in the gases, rejected into the atmosphere, a centrifugal force which results in urging them to take a direction transverse to the axis of the weapon and to become scattered in eddies in space; for this purpose, the gases, after having passed through the nozzle or nozzles and the corresponding deflector system or systems, are discharged directly into the atmosphere through openings of helicoidal shape, the pitch of which is preferably shorter than that of the rifling in the bore of the gun and shorter than the pitch of the helical ridges of the nozzles when the latter are helically ridged.

This device is especially applicable to guns intended for arming aircraft where the high speed of movement of the apparatus and the very low temperature of the air in which it travels, aid the blowing out of the gases and their dispersion.

This arrangement allows of obtaining a reduction of the dimensions and weights, which may even reach a reduction of the diametrical overall size below two calibres.

In the annexed drawings:

Fig. 1 represents, by way of example, in a view partly in axial longitudinal section, partly in external view, a form of carrying out the invention

in its application to a three-expansion recoil-absorber, comprising three nozzles and the corresponding deflector-systems.

Fig. 2 is a view in perspective of a modification of the muzzle check;

Fig. 3 is a view in side elevation of this modification, partly in vertical section, the muzzle check being represented in broken lines;

Fig. 4 is a view thereof in rear end elevation;

Fig. 5 is a view in plan from above; and

Fig. 6 is a view in axial longitudinal section of the muzzle check, showing a detail of construction of the latter.

Referring to Fig. 1 of the drawings, *a* designates the barrel of a firearm, *b* a first convergent-divergent nozzle screwed to the front extremity of the barrel; *c* and *d* two other convergent-divergent nozzles, mounted in front of the first and fixed like the latter to the casing *e*; *f* designates an obturator, mounted in front of the third nozzle *d* and comprising a grooved cylindrical axial passage *f*¹ for the discharge of the projectile; *b*¹, *c*¹, *d*¹ (each) designate an annular passage or throat, generated by the revolution, around the longitudinal axis *x*—*x* of the barrel of the weapon of the curved profile of the rear face *c*², *d*², *f*², turned towards the weapon, of the nozzles *c*, *d* and obturator *f*; these passages or throats *b*¹, *c*¹, *d*¹ constitute a kind of fixed deflector-systems. The nozzles *b*, *c*, *d* are preferably of the type described in the French Patent No. 717,736 dated September 17, 1930, that is to say that they are grooved in such a way as to give the gases, passing through these nozzles, a movement of rotation around the axis of the letter, owing to the provision of helical ridges *b*³, *c*³, *d*³. Of course, these helical ridges turn in the same direction as the rifling of the bore of the gun. Preferably, the pitch of helical ridges *b*³ is shorter than that of said rifling. In a likewise manner, the pitch of the ridges *c*³ of the second nozzle *c* will be shorter than that of ridges *b*³, and the pitch of the ridges *d*³ of the third nozzle *d* still shorter than that of the ridges *c*³ of the second nozzle.

The gases, thus animated with an extremely rapid movement of rotation around the axis *x*—*x* of the weapon, will escape through the deflector systems *b*¹, *c*¹, *d*¹. They are then discharged directly into the atmosphere through openings *e*¹, *e*², *e*³ formed in the casing *e*: these openings are of helicoidal shape, in such a way as not to oppose the helicoidal rotation of the gases, but on the contrary to further accelerate the latter; with this object, the walls or arms *g*, which extend between these openings, are given the shape

of helical surfaces, turning in a direction opposed to that of the grooving of the nozzles and preferably of a pitch still shorter than that of the grooving of the nozzles.

5 These arms or walls *g* may be so arranged as not to coincide with the places where the ridges of the nozzles, if prolonged, would intersect the deflectors, in order to avoid the formation of eddies which would interfere with the flow and the efficiency.

10 The number of openings *e*¹, *e*², *e*³ and arms *g* and their dimensions can vary according to the conditions of each particular case.

15 With this device, the gases are therefore urged to continue to turn in the direction of the rifling of the weapon, but much faster and with a rearward movement when they have passed over the deflector systems. The centrifugal effect which results therefrom tends to scatter them in the 20 air and in any case to make their path diverge from that which they would follow if they were purely and simply rejected towards the rear.

25 In the example of construction represented, an assembly device has been worked out in order to combine these desiderata, with as great as possible a reduction of the overall size.

30 The first nozzle *b* comprises longitudinal beaks or extensions *b*⁴, which are preferably of the same number as the walls or arms *g* and which 35 present corresponding dimensions; these beaks or extensions *b*⁴ are arranged against the inner face of the arms *g* and are profiled in such a way as to direct the gases between the latter, thus fairing these arms or walls *g* internally; these beaks or 40 extensions serve moreover to regulate the spacing between the nozzle *b* and the corresponding deflector-system *c*².

45 The nozzles *c* and *d* comprise corresponding beaks or extensions *c*⁴ and *d*⁴; but stronger because they transmit a considerable portion of the thrust from the gases.

50 The deflector-systems *b*¹, *c*¹ are constituted only in part by the curved rear face *c*², *d*² of the nozzles *c*, *d* respectively; an outer part of these deflector-systems *b*¹, *c*¹ is constituted by an element of the rear face of the structure *e*, these parts being preferably assembled in such manner as to form a step at *i* in order to facilitate the construction.

55 The casing *c* is fixed to the first nozzle *b* by a screw-threading and/or by tap-screws *h*.

60 This casing transmits the checking force by the arms *g* and the obturator *f* and eventually by the pins *h*, either alone or in combination with the screw-threading.

A modification of construction consists in screw-threading the casing *e* internally as far as the obturator *f* (as represented in dotted lines in the drawings at *k*) and in mounting the various 65 parts by screwing; the thrust is thus transmitted to the casing *e* through the screw threading *k* and not by the beaks or extensions *b*⁴, *c*⁴, *d*⁴ of the nozzles *b*, *c*, *d*.

65 The assembling pins which serve likewise for the adjustment of the final position of the parts, may be with heads showing or with countersunk head; in the case where the casing is not screw-threaded internally, as represented at *k*, these pins support a portion of the forces by shear.

70 We have found that, in the case of firearms adapted to be mounted and to shoot close to the ground, the spent gases, rejected downwardly by the muzzle check, according to Fig. 1, could make the dust fly and thus interfere with the sighting.

75 Furthermore if the centrifugal action checks the

discharge of the gases sufficiently to prevent it from producing a blast strong enough to bother the shooter, the acid nature of the gases thus rejected into the atmosphere may disturb the shooter by irritating his eyes.

80 The auxiliary arrangements disclosed by Figs. 2 to 6 obviate these drawbacks. Two steel plates *l* are arranged, the one above and the other below the muzzle check *A* over the length of the latter and are connected to the latter, at the 85 front and rear, by transverse rings *m* and *n* respectively; these plates *l* are preferably reinforced and rendered more rigid by a central longitudinal rib *l*. These plates leave preferably, between the outer wall of the check and their inner face, 90 a free space such that they do not paralyze the flow of the gases leaving the openings in the casting of the muzzle check and that they do not increase too greatly the overall size of the apparatus. Tests have shown that the loss of efficiency 95 of the muzzle check is practically nil, on condition that the ring *m*, serving for the fixing of the blades at the rear upon the muzzle check (that is to say on the side of (towards) the shooter), has a frusto-conical shape, with the large base of 100 the cone frustum towards the rear (Figs. 3 and 5) each plate *l* is connected to the rear ring *m* by a wedge-shaped projection *o*, of which the apex is situated upon the front edge of the ring *m* and which opens out towards the rear.

105 Tests have shown that when the line of sight is lateral of the weapon, the wedge shaped member *o*, connecting the upper plate *l* with the rear ring *m*, should be shaped so as sufficiently to deflect the gases laterally from the line of sight, at 110 the rear of the device *A*, in order to protect the shooter's eyes from the gases. Figs. 4 and 5 show the case where the line of sight is located on the left hand side of the weapon (looking towards the front of the weapon, that is, on the left of 115 Fig. 4 and on the upper half of Fig. 5); in this case, the wedge-shaped projection *o*, connecting the upper plate *l* to the rear ring *m*, should have a profile such as that indicated at *o*¹, *o*², *o*³, in Fig. 5, instead of the profile such as indicated at 120 *o*⁴, *o*², *o*³, in this same Fig. 5. This latter profile corresponds to the case where the line of sight is situated in the longitudinal vertical axial plane of the weapon. In the first case, the face *o*¹, *o*² deflects the gases away from said plane more than 125 50 does the face *o*⁴, *o*² in the second case.

130 The front ring *n* must comprise a shoulder *n*¹, in order to prevent the escaping gases from pushing the device backwards. On the other hand, in order to prevent the helicoidal motion of the 135 escaping gases from revolving the device, constituted by the plates *l* and the rings *m*, *n*, upon the muzzle check, the ring *m* is assembled to the casing of the muzzle check by pins (grub-screws) *p*. The latter further secure the device, consisting of plates *l*, *l*, in its position of maximum efficiency, which is not that of the absolute horizontal of the plates, but a position slightly inclined to the horizontal, by reason of the helicoidal motion of the escaping gases. Fig. 4 represents this optimum position of inclination of the plates to the horizontal in the case of a weapon with right hand rifling.

140 Advantage can be taken of the shoulder or moulding *n*¹ on the front ring *n* in order to mount 70 at this position a frusto-conical mouth-piece *q* preferably made of duralumin, forming a flame screen in order to conceal the slight muzzle flash which the use of the device causes to reappear at the extremity of the muzzle check. In the case 75

where the weight of the device described above or any other reason should make desirable a reinforcement of the muzzle check proper, this reinforcement can be obtained practically without increase of weight, by the arrangement represented in Fig. 6; each of the deflectors b^1 , c^1 , d^1 , comprises, behind its outlet edge, upon the casing e , a beading r , so that each of the arms or walls g , between the helicoidal openings e^1 , e^2 , e^3 for the exit of the gases, is reinforced at the point where it is most subject to fatigue.

We claim:

1. A free exhaust recoil absorber for a gun having a barrel with a bore provided with riflings which comprises, in combination, at least one convergent-divergent nozzle at the front end of said barrel, coaxial with said bore, inward ridges carried by the inner wall of said nozzle, disposed helically around the axis of said bore, with a pitch shorter than that of said riflings, deflecting means rigid with said nozzle opposite the periphery of the front end thereof for rejecting in a rearward direction the gases issuing from said nozzle, a plurality of radial partitions rigid with said deflecting means and disposed helically about the axis of said bore in the space existing between the outer front end of said nozzle and the outer rear face of said deflecting means, said helical partitions turning in a direction opposed to that of said riflings and with a pitch shorter than that of said ridges, and two metallic plates rigid with said recoil absorber and disposed one above and the other below it, over the length thereof, so as to prevent the spent gases from interfering with the sighting.

2. A recoil absorber according to claim 1 further including rings for securing said plates to said recoil absorber at the front and rear part thereof.

3. A recoil absorber according to claim 1 in which said metallic plates are in a position slightly inclined to the horizontal, further including rings for securing said plates to said recoil absorber at the front and rear part thereof.

5

4. A free exhaust recoil absorber for a gun having a barrel with a bore provided with riflings, which comprises, in combination, a plurality of convergent-divergent nozzles arranged one behind another at the muzzle end of said barrel, all coaxial with said bore, ridges carried by the inner wall of said nozzles, arranged helically around the axis of said bore, the pitch of the ridges of each nozzle being shorter than that of the ridges of the nozzle located nearer to the muzzle of the barrel and the pitch of the ridges of the nozzle immediately adjacent to the barrel being shorter than the pitch of the riflings of the said barrel, deflecting members, rigid with said nozzles, located opposite the periphery of the front end of each of them for rejecting outwardly, in a transverse and somewhat rearward direction, directly into the atmosphere, the gases issuing from said nozzles, a plurality of radial partitions rigid with said deflecting members and arranged helically about the axis of the bore in the space existing between the outer front end of each of the said nozzles and the outer rear face of the said deflecting member located immediately ahead of said nozzle, said helical partitions turning in a direction opposed to that of the riflings and of the ridges of the nozzles and with a pitch shorter than that of the said ridges, and outward projections on said deflecting members arranged to reinforce said partitions.
